Specification of Reissued Letters Patent. Reissued Aug. 8, 1911.

Original No. 913,299, dated February 23, 1909, Serial No. 447,358. Application for reissue filed March 9, 1911. Serial No. 613,475.

To all whom it may concern:

Be it known that we, CHARLES H. MARSTON and HENRY H. CUMMINGS, residents, respectively, of Reading and Newton, in the county of Middlesex and State of Massachusetts, have invented certain new and useful Improvements in Apparatus for Marking Checks, of which the following is a specification.

- 10 This invention relates to apparatus for imprinting on the backs of bank checks the usual printed information which is placed on the check after its reception in the bank where it is payable, the printed information 15 being usually applied by a rubber printing member, giving the name of the bank, the name of its cashier or other officer, the date, etc.

The invention has special reference to 20 apparatus of the general character set forth in Letters Patent of the United States, No. 865,050, dated September 3, 1907. The apparatus disclosed by said patent comprises an adding machine which is caused to print 25 on a record sheet the amounts represented by the checks handled during a given period, the adding machine being provided with keys which set the printing characters of the machine, and with an oscillatory lever 30 which is manually moved in one direction by the operator, and is automatically moved by a spring or otherwise in the opposite direction when the operator releases it. The operator facing the machine, takes up the 35 checks one by one, holding each check in one hand while manipulating the keys of the adding machine to adapt the machine to print the amount represented by the check. After the machine has been set to print the 40 amount of one check, the operator moves the lever forward, and thus causes an impression by the printing mechanism of the amount of the check on the record sheet. When the operator releases the lever, it is 45 automatically returned to its starting position, and the record sheet is at the same time fed along, this operation being repeated for each check. The said patent also discloses a printing couple, the members of 50 which are rotated during one movement of the said operating lever, and remain at rest

during the opposite movement so that the printed indorsements are applied to the checks at the same time that the adding machine is being operated to record the amounts of 55 the checks, thus saving the delay and loss of time involved when a separate operation apart from the adding machine is required for affixing the printed indorsements. In said patented apparatus the printing mechanism is operated by the power exerted by 60 the operator in moving the lever of the adding machine, as above described.

The present invention has for its object, first, to provide a check-marking apparatus, 65 the printing mechanism of which shall be operated by power independent of that applied to the lever of the adding machine, the printing mechanism being operated by power, preferably supplied by a small electric motor, which is normally disconnected from the printing mechanism, and is adapted to be connected with said mechanism by the forward movement of the lever of the adding machine, or by means independent 75 of said lever.

The invention also has for its object to provide certain improvements relating to the printing mechanism, some of said improvements being capable of use in the type 80 of check-marking apparatus shown in the said Letters Patent.

The invention consists in the several improvements which we will now proceed to describe and claim.

85 Of the accompanying drawings forming a part of this specification, Figure 1 represents a front elevation of a check-marking apparatus embodying our invention, and an adding machine with which the marking apparatus is connected. Fig. 2 represents a section on line 2—2 of Fig. 1, and an elevation of the mechanism at the left of said line. Fig. 3 represents a section on line 3—3 of Fig. 2. Fig. 4 represents a section 90 on line 4—4 of Fig. 1, and an elevation of the mechanism at the right of said line. Fig. 5 represents a section on line 5—5 of Fig. 2. Fig. 6 represents a section on line 6—6 of Fig. 1. Fig. 7 represents a section 100 on line 7—7 of Fig. 1. Fig. 8 represents a section on line 8—8 of Fig. 5. Fig. 9 repre-

sents a section on line 9—9 of Fig. 5. Figs. 10, 11 and 12 represent side elevations of portions of the mechanism for connecting the printing mechanism with the motor.

5 The same characters of reference indicate the same parts in all the figures.

In the drawings 12 represents the casing of an adding machine which may be of any suitable form, the form here shown being 10 that of the Burroughs adding machine.

13 represents the oscillatory operating lever of the machine, said lever being normally held by a spring or otherwise, as usual, in the position shown in Fig. 4, and adapted 15 to be manually moved by the operator to a forward position, the movement of the lever to the last mentioned position causing the printing characters of the machine to make an impression on a record sheet at the back 20 of the machine. When the lever is released, after being pulled forward by the operator, it is returned by its controlling spring to its normal position.

To the casing 12 is affixed a suitable frame 25 adapted to support the printing mechanism hereinafter described, said frame comprising a base 15, and suitable frame parts associated therewith, the frame being attached in a detachable manner to the end of the casing 30 12 opposite the end at which the lever 13 is located. The means for thus attaching the frame consists of studs 151, 152 and a socket 153 on the adding machine case; lugs 154, 155 and a tongue 156 on the frame; and pins 35 157, 158. The tongue 156 is stepped in the socket 153, the lugs lie beside the respective studs, and the pins 157, 158 pass through and into respectively adjacent studs and lugs, one or both of the pins being removable from 40 the parts which it enters.

16 represents the printing or impression member or roll, and 17 the bed member or roll of a printing couple, these members being rotated simultaneously in opposite directions by the mechanism hereinafter described.

The impression member is provided with one or more segmental forms or plates 18, which may be of elastic material and adapted 50 to impress the printed indorsement upon the back of a check passed between the two members. The impression member 16 is mounted on a shaft 19 which is journaled in bearings 20 on the supporting frame.

55 21 represents the casing of a small electric motor which is preferably mounted on the base 15, and may be connected by any suitable means with a source of electricity such as an incandescent lamp socket. The shaft 60 22 of the motor rotates in frictional contact with a wheel 23, the shaft 24 of which is journaled in a bearing 241 which is supported upon the frame by an articulated connection including an arm 242 pivoted at 243 to a second arm 244, which in turn is pivoted

at 245 to the frame. For securing strength and stiffness these arms are preferably made of relatively great width as compared to their length, and so have an extended bearing or a plurality of bearings on their pivot 70 pins 243 and 245 respectively. A screw abutment 246 is threaded through a fixed part of the frame and bears against a lug 247 on the arm 242. By adjusting the screw 246 the rim of wheel 23 may be pressed with more 75

or less force against the motor shaft 22. The wheel 23 is provided with a pulley 25, which is connected by a belt 26 with a pulley 27 on a shaft 28, which is also journaled in bearings on the supporting frame. The screw 80 246 also serves to adjust the tension of the belt 26, and the reaction of the belt causes the pressure of the screw to force the wheel 23 downward against the armature shaft. To the shaft 28 is affixed a gear 29 meshing 85 with a gear 30, which is loosely mounted on the shaft 19. The gear 30 carries a suitable clutch member which is adapted to engage a complementary clutch member carried by the shaft 19, the arrangement being such that 90

when said clutch members are connected, rotation will be imparted from the shaft 28 to the impression roll shaft 19 through the gears 29 and 30. When said clutch members are separated, which is their normal condition, the rotation of the impression roll shaft 95 19 stops. In this embodiment of our invention, the clutch member on the loose gear 30

is an annular series of radial teeth 31 formed on one side of the loose gear 30. The clutch member carried by the impression roll shaft 100 is an arm 32 pivoted at 33 to ears formed on a head 34 which is rigidly affixed to the impression roll shaft 19. The swinging end portion of the arm 32 is provided with a tooth 35 adapted to engage either of the radial teeth 31 when the arm 32 is swung inwardly from the position shown in Fig. 5 toward the head 34, the arm being normally held in the position shown in Fig. 5 by a detent member 36, so that the clutch teeth 31 and 35 are normally disengaged, the impression roll shaft being, therefore, normally 105 at rest. The detent 36 is an arm which is pivoted at 37, and is normally held in the

110 depressed position shown in Figs. 2 and 12 by means of a spring 38, so that the detent normally bears upon the outer surface of the annular flange on which the radial teeth 31 are formed. The arm 32 is normally pressed 115

inward to engage a tooth 31 by means of a spring 39 which is fastened at one end by a screw 391 to the arm, and at its other end passes through a pin 392 secured to the head 34, thus exerting an inward pressure on the arm when the detent 36 is raised, as shown in Figs. 10 and 11, and by dotted lines in Fig. 5. It will be seen, therefore, that when the detent 36 is raised, the tooth 35 of the arm 120 32 moves into engagement with one of the 125 130

teeth 31, thus establishing a connection between the loose gear 30 and the impression roll shaft 19. When the detent 36 is depressed, as shown in Figs. 2 and 12, and by full lines in Fig. 5, it encounters the outer end of the arm 32 and forces said arm to the position shown in Fig. 5 in disconnecting the members of the clutch. The detent 36 is wedge-shape, or has an inclined side face 10 which encounters the swinging end of the arm 32 whenever the rotation of the gear 30 brings the arm 32 to the point occupied by the detent 36. When the arm encounters the detent and is displaced thereby, the rotation 15 of the arm of the impression roll shaft ceases, the arm remaining in contact with the detent, and the impression roll remaining at rest until the detent is again raised to permit the engagement of the clutch members. 20

From the foregoing, it will be seen that the printing mechanism is operated only when the detent 36 is raised and becomes inoperative, and remains at rest when the 25 detent is depressed.

The adding machine is provided with mechanism for feeding a record sheet 40 step by step, each feed movement of the record sheet being effected during the 30 return movement of the lever 13 to its rearward position after it has been pulled forward and released by the operator. The said mechanism includes a rock shaft 41 and mechanism for rocking the same. 35 Said mechanism forms no part of our invention, and therefore is not here shown in its entirety. The said mechanism includes an arm 42 which is affixed to the rock shaft 41, and is connected by a rod 43 with an arm 44 which carries a pawl 45 engaging a ratchet 46 on a shaft 47, which imparts a step-by-step rotation to a feeding and impression roll 48.

We have utilized the rock shaft 41 and its 45 arm 42 as a part of the mechanism for connecting the clutch members above described, and thus imparting rotation to the impression roll shaft 19, our adding mechanism including suitable connections between the arm 42 and the detent 36, shown clearly in 50 Figs. 2, 10, 11 and 12.

55 50 represents a lever pivoted at 51 to the supporting frame. One arm of the lever is connected by a rod 52 with the adding machine arm 42. The other arm of the lever 50 carries an ear 53 which projects laterally from the lever (see Fig. 3), and has an inclined curved outer face 54 (Fig. 11). The lever 50 is normally in the position 60 shown in Fig. 3, its face 54 overhanging a stud 55 on an arm 56 which is mounted to oscillate on the pivot stud 37, on which the detent 36 is mounted, the detent and the arm 56 being adapted to oscillate to a limited extent independently of each other. The

arm 56 is provided with an ear 57 which is yieldingly held by a spring 58 against an arm 59 affixed to the detent 36, said spring being fastened to a part of the detent 36. The normal position of the lever 50, shown 70 in Fig. 3, is the position which the lever occupies while the lever 13 of the adding machine is being moved forward by the operator, and until the lever 13 is returned to its rearward position. 75

The rock shaft 41 and its arm 42 are normally in the position shown in Fig. 4, the rock shaft being moved from said position by mechanism actuated when the lever 13 returns to its rearward position in such manner as to raise the arm 42 from the position shown in Fig. 4, thus raising the rear arm of the lever 50 and depressing the forward arm having the ear 53, and causing the inclined face 54 of said ear to act on the stud 80 55 and move the arm 56 forward against the arm 59, thus raising the detent, as shown in Fig. 11, and causing it to release the clutch arm 32, the tooth 35 carried by said arm being allowed to engage one of the clutch 85 teeth 31 of the loose gear 30. The detent 36 remains in its raised position only while the ear 53 is in contact with the stud 55, the spring 38 acting as soon as the ear 53 passes below the stud 55, as shown by dotted lines 90 95 in Fig. 11, to force the detent downwardly into position to displace the clutch lever 32.

In practice, the detent lever 36 remains raised during less than a complete rotation 100 of the impression roll shaft 19, so that it is in position to displace the clutch arm 32 when the impression roll has made a complete rotation.

When the detent is depressed, its arm 59 forces the arm 56 backwardly so that the 105 stud 55 passes over the upper end of the ear 53 while the lever 50 is in the dotted line position shown in Fig. 11. When the lever 50 returns to its normal position, shown in Fig. 3, the inclined face of the ear 53 moves upwardly in front of the stud 55, the latter yielding to the ear and swinging backwardly until the ear passes above it, the spring 58 then acting to return the arm 56 and stud 55 to the position under the ear 110 115 53 shown in Figs. 2 and 3, so that the parts are again ready to act to raise the detent when the lever 50 is again moved from its normal position.

It will be seen from the foregoing that 120 after each forward movement of the adding machine lever 13, and its release and automatic return to its rearward position, the detent 36 is raised, and the impression roll shaft 19 is connected with the motor until it has made a complete rotation, and is then automatically disconnected from the motor and stops.

A hopper 60 guides the checks to the nip 125 of the printing couple rolls, the arrange- 126

ment being such that a check dropped in the hopper will be engaged by said rolls and drawn between them, the check being impressed by the printing characters on the impression roll, and then delivered through the contracted throat 61 of the hopper. This hopper conveniently consists of an end wall 61^a which may be an integral part of one of the side frames of the apparatus, a rear wall 61^b and a front wall 61^c. The rear wall is supported by an arm or rib 61^d which is made as a part of the frame, and the front wall is removably supported, being provided with an apron 61^e, which makes an acute angle with the front wall. A stud 61^d on the end wall of the hopper is received in this acute angle and supports the front wall and apron, the lower edge of the apron being held between a cross rib 612 of the frame and a table 613. The walls 61^b and 61^c of the hopper are widely separated at their upper ends and converge toward the nip of the rolls, thereby forming guides which guide the checks properly into the position for printing. The hopper is open at the end opposite to the wall 61^a, so that checks may be placed in the hopper with their ends projecting therefrom, if it is necessary to place them in such a position in order to present a clear space to the action of the printing roll. As the printing roll is placed at a considerable distance from the closed end of the hopper, it is thus possible to apply the indorsement to any part of the back of a check. The table 613 and apron 61^e provide a receptacle for the unstamped checks, upon which such checks may be placed in position for being conveniently picked up and read.

It will be observed that the operation of the printing mechanism is attended by practically no resistance to the movement of the adding machine lever, the force required to raise the detent 36 and thus permit the connection of the impression roll shaft to the motor being practically inappreciable.

To enable the adding machine to be operated without operating the printing mechanism, we provide a lever 62 pivoted at 63 to the supporting frame which is adapted to play between fixed stop pins 64. The outer arm of the lever 62 is provided with a finger key 65 adapted to be depressed by the operator, as indicated in Fig. 12. The opposite end of the lever is provided with an inclined face 66 which bears against the stud 55 on the arm 56 when the key is depressed, and forces said arm and stud backwardly so that the stud is out of the path of the ear 53; hence the previously described movements of the lever 50 have no effect upon the detent arm, the latter remaining in its depressed position, and holding the clutch arm 32 out of engagement with the clutch 31. When the key 65 is

released, the lever 62 assumes the position shown in Figs. 2, 10 and 11, so that its rear end is below the stud 55.

We have provided means whereby the printing mechanism may be operated independently of the adding machine whenever this is desirable. Said means, as here shown, comprise a lever pivoted at 68 to the supporting frame, and having an upwardly projecting longer arm 67 located behind the hopper 60, and a downwardly projecting shorter arm 69 which is connected by a link 70 with the arm 59 of the detent 36. The arm 67 is normally in the position shown in Figs. 2, 4, 10 and 11. When the said arm is moved to the position shown in Fig. 10, the shorter arm 69 acts through the link 70 to move the arm 59 and detent 36 to raise the detent, thus permitting the connection of the clutch members so that the impression roll is rotated. The arm 67 is provided with an elongated ear 71 (see Figs. 1 and 5), which extends practically the entire length of the hopper 60, and is located a little in advance of the rear wall of the hopper, as shown in Fig. 4, so that the operator's hand in inserting a check in the hopper may readily move the lever arm 67 from the position shown in Figs. 4 and 12 to that shown in Fig. 10, and thus cause the raising of the detent and the raising of the clutch members.

When the pressure of the operator's hand is removed from the ear 71, the lever 67 returns to its normal position, permitting the depression of the detent 36.

The impression roll 16 is, as above stated, preferably secured detachably to its shaft 19, the connecting means being shown in Fig. 5 as consisting of a wheel 72 affixed to the shaft 19 and provided at its inner side with a recess having a beveled margin 73, and a similar wheel 74 mounted to slide on the shaft 19 and rotatively engaged with the latter by means of a key 75 on said shaft engaging the groove in the hub of the wheel, said wheel having in its inner side a recess with a beveled margin 76.

The ends of the impression roll are provided with projections having beveled concentric margins 77, which fit the margins of the recesses in the wheels 72 and 74. One end of the impression roll has a dowel pin 78 adapted to enter an orifice formed for its reception in the wheel 72, to insure the proper relative position of the impression roll on its shaft. The slidable wheel 74 is pressed yieldingly against the corresponding end of the impression roll by the spring 79. When it is desired to remove the impression roll, the wheel 74 is moved away from the impression roll, the latter being free to be moved out of engagement with the wheel 72 and from the shaft 19. One side of the impression roll is cut away, as shown

in Fig. 6, and provided with a recess 80 which receives the shaft 19. This construction permits the impression roll to be applied to and removed from the shaft by a 5 lateral movement.

81 represents an inking roll affixed to the shaft 28, and rotated by the latter in contact with an inking pad 82 contained in a recess in the bottom of a trough 83. Said 10 trough is mounted to have a slight oscillating motion on a removable pin or stud 84 supported by sockets 85, 86 on the supporting frame. The trough is provided with a doctor-blade or scraper 87 which bears 15 against one side of the periphery of the inking roll and removes the surplus ink therefrom. A spring 88 secured at one end to the supporting frame, and bearing at one end on a flange formed on the trough 83 presses the 20 scraper 87 yieldingly against the periphery of the inking roll.

Provision is made for releasing the shaft 28 so that the inking roll may be removed, and also for adjusting such shaft with the 25 inking roll toward or from the printing roll. For this purpose the end of shaft 28 opposite to that on which the pulley 27 is mounted is contained in a bearing 811 which is shown in detail in Fig. 8 and is formed as 30 a socket in an arm 812 which is pivoted to one of the side members of the frame at 813. To a part of the arm or bearing is secured a resilient plate or strip 814 which has at one point a slot 815 substantially radial to 35 the bearing 813. A pin 816 is mounted rotatably and removably in a part of the frame and has an eccentric projection 817 which enters the slot 815. By rotating the pin the bearing 811 and with it the shaft 28 40 and roll 81 may be moved up or down, that is toward or from the printing roll. By disengaging the projection 817 from slot 815 the bearing 811 may be lowered clear of the shaft, leaving the end of the latter 45 free so that the roll may be slipped off. Previous removal of the ink trough permits such removal of the roll. The bearing for the opposite end of the shaft 28 is 50 arranged to permit slight oscillation of the shaft, and consists of a box 819 contained in a bracket 820 rigidly affixed to one of the side frames of the apparatus. The box is connected to the bracket by a pin 821 transverse to the shaft which permits an up and 55 down swinging movement of the opposite end of the shaft.

The wheels 72 and 74, which engage the ends of the impression roll, are provided with frictional bands or tires 89, which 60 frictionally engage the periphery of the bed roll 17, and constitute a friction drive for the bed roll. The shaft 19 is preferably provided with two additional wheels 90, each having a rubber semi-frictional tire 89, 65 these engaging the periphery of additional

rolls or disks 77. Such disks guide the checks and prevent them from becoming displaced while in contact with the printing types and thus blurring the impression. The wheels 90 and disks 17' are respectively on opposite sides of the printing couple and at some distance therefrom, thus furnishing valuable aid in steadyng the checks. 70

Provision is made for adjusting the bed roll 17 and disks 17' toward or from the printing roll and wheels 90, to control the gripping pressure exerted by these rolls and wheels. For this purpose the roll 17 and disks 17' are journaled upon a spindle 891 which has a journal 892 contained in a bearing 893 on one of the side members of the apparatus frame. The spindle 891 is eccentric to the journal, and between such spindle and journal is a capstan head 894 by which the spindle may be turned. Such turning brings the spindle and the parts carried thereby nearer to or farther from the printing roll shaft 19. The outer end of the bed roll spindle is contained in an arm 895 which is connected to the rear wall 61^b of the hopper, said arm having a bearing 896 which is concentric with the bearing 893 previously described. Mounted upon that part of the spindle 891 which is contained in the bearing 896 is a thimble 897 of equal and opposite eccentricity to the spindle itself. This thimble is connected to the spindle in proper angular relation by the key 898 so that it remains concentric with the journal 892. 80

90 95 100 105 110 115 120 125 130

91 represents a fly for taking the checks as they issue from the printing couple and laying them in a pile which is located below the outlet 61 of the hopper, and is adapted to oscillate between the full and dotted line positions shown in Fig. 4, the fly being normally in the full line position so that a check emerging from the hopper will lie against it, and will be carried over by the movement thereof to the dotted line position, and dropped upon the base 15. The fly 91 consists preferably of a number of wires or rods affixed to a rock shaft 92, which is journaled in bearings in the supporting frame, and has an arm 93 which is connected by a rod 94 with an arm 95 pivoted at 96 to an ear on the supporting frame. The arm 95 is provided with a projection 97 having a curved lower edge formed and arranged to be engaged by a stud 98 which projects from one side of one of the wheels 90 on the impression roll shaft 19. The fly 91 stands normally in the position shown by full lines in Fig. 4, the projection 97 being so arranged that when the stud 98 is carried in the direction indicated by the arrow shown on the wheel 90 in Fig. 4, said stud will strike the under side of the projection 97 and raise the arm 95 to the position shown in dotted lines, thereby turning the rock shaft 130

92, through the rod 94, and throwing the fly to the position indicated by dotted lines. When the stud 98 passes from under the projection 97, the arm 95 and the fly return to their normal positions.

We claim,

1. In combination, an adding machine, a printing couple, a motor, connections between the motor and the printing couple, 10 including a clutch, means controlled by an operator for causing the engagement of the clutch members, and automatic means for separating the clutch members.

2. In combination, an adding machine, a printing couple, a motor, connections between the motor and the printing couple, including a clutch, the members of which are adapted to automatically engage, a detent adapted to separate said members, and 20 means for moving said detent to alternately permit the engagement and cause the disconnection of the clutch members.

3. In combination, a printing couple, a motor, connections between the motor and 25 the printing couple including a clutch, an adding machine and mechanism intermediate the said clutch and a movable part of the adding machine for alternately causing the engagement of the clutch members and 30 separating the same.

4. In combination, a printing couple, a motor, connections between the motor and the printing couple, including a clutch, one member of which is yieldingly mounted and 35 adapted to automatically engage the other member, a detent adapted to separate said members, an adding machine, and connections between said detent and a movable part of the machine whereby the detent is 40 caused to alternately displace and release the yielding clutch member.

5. In combination, a printing couple, a motor, connections between the motor and the printing couple, including a clutch, an 45 adding machine, mechanism intermediate the said clutch and a movable part of the adding machine for alternately causing the engagement of the clutch members and separating the same, and means for making 50 said intermediate mechanism inoperative, to permit the operation of the adding machine only.

6. In combination, a printing couple, a motor, connections between the motor and 55 the printing couple, including a clutch, an adding machine, mechanism intermediate the said clutch and a movable part of the adding machine for alternately causing the engagement of the clutch members and separating the same, and auxiliary mechanism 60 for causing the engagement and separation of the clutch members independently of the adding machine.

7. In combination, a printing couple, a 65 motor, connections between the motor and

the printing couple, including a clutch, one member of which is yieldingly mounted and adapted to automatically engage the other member, a detent adapted to separate said members, an adding machine, connections between said detent and a movable part of the machine whereby the detent is caused to alternately displace and release the yielding clutch member, and a key lever adapted to make said connections inoperative.

8. In combination, a printing couple, a motor, connections between the motor and the printing couple, including a clutch, one member of which is yieldingly mounted and adapted to automatically engage the other member, a detent adapted to separate said members, an adding machine, connections between said detent and a movable part of the machine whereby the detent is caused to alternately displace and release the yielding clutch member, an auxiliary operating lever located adjacent to the printing couple, and connections between said lever and the detent whereby the latter may be operated independently of the adding machine.

9. In combination, an adding machine, a printing couple, a motor, and means connected with a movable portion of the adding machine for controlling the operation of the printing couple by said motor.

10. The combination of a support, a printing roll rotatably mounted on said support, a bed or impression roll mounted beside the printing roll, a motor adapted to be driven continuously, a rotating clutch member driven by said motor, a complementary clutch member in connection with the printing roll, normally inoperative means tending to cause inter-engagement of said clutch members, a detent normally holding said members out of engagement, and a lever having an operative connection with said detent and adapted to be manually operated for rendering the detent inoperative.

11. In a combination of the character described, a check-marking device, comprising a normally inoperative printing member, a coöperating bed member, guide members for receiving and conducting a check to a position between said members, a continuously running motor, a clutch including two separable members, driving mechanism operated by said motor for keeping one of said members in motion, connections through which the other of said members, when driven, actuates the printing member, yielding means tending to put said clutch members into engagement, a detent normally arranged to hold the members out of engagement, and manually controlled mechanism for displacing said detent into an inoperative position, including an actuator having a part in such close proximity to said guiding members that it may be moved by the

hand which places the check between the guiding members.

12. An apparatus for the marking of checks, comprising coöperating printing and bed members adapted and arranged to press a check between them, a hopper or check guide above said members having guides arranged to admit a check and conduct the same to said members, a clutch member having a positive connection with said printing member so that when driven it drives the same, a complemental clutch member unconnected with the printing member, an operating lever having an arm extending in close proximity to said hopper, and means controlled by said lever for causing engagement and disengagement of the clutch members.

13. An apparatus for marking checks comprising a pair of rolls rotatably mounted in close proximity, one of said rolls bearing marking devices, a hopper above said rolls having walls converging toward the nip of the rolls, adapted to receive and guide a check to the rolls in position to be printed thereby, a shaft upon which one of said rolls is mounted, a clutch member loosely supported upon said shaft so as to be rotatable freely thereon, a complemental clutch member secured to the shaft and movable into and out of engagement with the first clutch member, a continuously running motor, connections between the motor and

the first clutch member for continuously rotating the latter, a detent member movable into and out of a position between the clutch members so as to separate the members from interengagement when in such position, means tending to cause interengagement of the clutch members, and an operating arm having a connection with said detent for moving it out of such position.

14. An apparatus for marking checks, comprising complemental rolls one of which carries marking devices and the other of which serves as a bed, a continuously running motor, a clutch member driven by such motor and running independently of either roll, a complemental clutch member having a positive driving connection with one of the rolls and adapted to be connected with and disconnected from the first-named clutch member, means for causing connection and disconnection of such clutch members, and a lever for operating such means mounted adjacent to the rolls and having an arm located where it may be moved by the hand of the operator when placing a check in position to be engaged by the rolls.

In testimony whereof we have affixed our signatures in the presence of two witnesses.

CHARLES H. MARSTON.
HENRY H. CUMMINGS.
